UNITED STATES PATENT OFFICE.

HENRY PATTBERG, OF JERSEY CITY, NEW JERSEY.

CASE FOR TOILET-SETS.

SPECIFICATION forming part of Letters Patent No. 279,272, dated June 12, 1883.

Application filed April 21, 1883. (No model.)

To all whom it may concern:

Be it known that I, HENRY PATTBERG, of Jersey City, in the State of New Jersey, have invented new and useful Improvements in 5 Cases for Toilet-Sets, of which the following is a specification.

The nature of my invention consists in the arrangement of a sliding cushion acted upon by a spring or springs in the upper end of the 10 tray or frame which receives a mirror, which said spring-cushion acts against the upper end of the mirror and holds the same tight between it and the lower end of the tray independent of the length or shape of the mirror, and dispensing with the usual side projections and 15 latches for holding the mirror in place.

In the accompanying drawings, Figure I represents a plan of a tray embodying my improvement holding an oval mirror. Fig. II is 20 a plan of a tray holding a square mirror considerably smaller. Fig. III is a longitudinal section at line *x x*, Fig. I; and Fig. IV is a cross-section at line *y y*, Fig. I.

Similar letters represent similar parts.

25 A represents the tray or frame, of the required shape to fit the toilet-case, the bottom B being formed of thick paper, card-board, or other suitable material in the usual manner. At the lower end of this tray the usual blocks, 30 C C, are attached, forming a recess or cavity in the middle to receive the end of the mirror-handle.

D is a frame moving freely in slots *a* in the sides of the tray A, in the upper end of the 35 same, and provided with a projecting cross-piece, J, under which the upper end of the mirror is passed, to prevent the same falling out.

Between the upper end of this frame D and 40 the upper end of the tray A either a flat spring,

E, or two or more spiral springs are arranged, forcing this frame D downward. The inside of the tray A, the blocks C C, as well as the frame D, are covered with silk, velvet, or other suitable fabric in the usual manner, the upper 45 end of which is made sufficiently loose to allow the free movement of the frame D.

The upper end of the mirror is placed underneath the projecting cross-piece J on the frame D, and said frame D forced upward 50 against the action of the spring E until the lower end of the mirror-handle can be passed into the tray A at the bottom, whereby the mirror will be held firmly between the bottom of the tray A and the frame D without requiring any latches, hooks, or other contrivance, and permitting an oval mirror, M, as shown in Fig. I, or an oblong mirror, M', as shown in Fig. II, considerably shorter, to be held and secured in the same tray. One size of tray will 55 thus answer for mirrors of different shapes and sizes.

What I claim as my invention, and desire to secure by Letters Patent, is—

1. A tray, A, for holding a mirror, constructed, substantially as herein shown and described, with a sliding spring-frame, D, at its upper end, for receiving the upper end of the mirror, as and for the purpose described. 65

2. In combination with a tray, A, the sliding frame D and spring E, or its equivalent, adapted to press against the upper end of a mirror resting against the bottom part of the tray, substantially in the manner and for the purpose set forth. 70

HENRY PATTBERG.
